ABSTRACT

A watch comprises a dial formed by a metallic bottle cap carrying an advertising inscription visible through transparent top and middle parts of a watch case. A synthetic material lining in the cap supports a watch movement housed therein.

2 Claims, 2 Drawing Figures

PATENTED APR 18 1972

3,656,292

FIG.2

**WRIST-WATCH WITH BOTTLE CAP DIAL AND
MOVEMENT HOLDER**

Wrist-watches are already known in which the movement is housed in a metallic dome-like member, the outside of the top surface of the dome-like member forming a dial and the side walls forming a frame for fitting the movement in a watch case. Moreover, it has already proposed to manufacture a watch-case entirely molded in plastic material.

It is an object of the invention to provide, by the original and eye-striking use of a common bottle cap or capsule according to these known techniques, a watch which has an unusual but appealing appearance and which is particularly suitable for use as an advertising medium.

A watch according to the invention comprises the combination of a case comprising an upper face, a middle and a bottom, at least the upper face and the middle being in transparent material, and a metallic bottle cap comprising a flat circular upper part and a flange forming a skirt extending around and out of the plane of said upper part, said cap being housed in said case with an outer surface of the upper part and skirt visible through the transparent upper face and middle of the case, a watch movement being housed in a space between an inner surface of the upper part of the bottle cap and an inner surface of the skirt of the bottle cap, a central hole being provided through the upper part of said bottle cap for the passageway of at least one pipe carrying a time indicating member rotatably driven above the upper part of said cap by means of said movement.

The accompanying drawings show, schematically and by way of example, an embodiment of the invention. In the drawings:

FIG. 1 is a plan view of this embodiment; and

FIG. 2 is a cross-section along line II-II of FIG. 1.

The watch shown comprises a case formed of two molded elements 1 and 2 of transparent synthetic material welded or stuck together.

The element 1 simultaneously forms a watch glass and a

middle of the case and carries horns for affixing a watch strap, whereas the element 2 forms a bottom. A conventional watch movement 3 is housed inside a metallic capsule of a bottle, in which synthetic plastic material 5 is injected to form a support

5 for the movement. A visible upper face 4a of the capsule 4, comprising an advertising inscription such as the trademark of a beverage, forms a dial. For this purpose, a hole is provided through the center of the capsule for the passage of pipes 6 carrying watch hands in a conventional manner. The inscription is preferably aligned in a manner to facilitate reading, for example by placing the inscription symmetrically in relation to the 12 o'clock-6 o'clock axis.

The entire upper surface 4a of the capsule 4 is visible through the upper element 1 of the watch case. The movement is visible through the bottom element 2 or, alternatively, the bottom element 2 can be made in opaque material.

The described watch can be manufactured at a low cost price and forms an excellent advertising medium.

What is claimed is:

- 20 1. In a watch, the combination of a case comprising an upper face, a middle and a bottom, at least the upper face and the middle being in transparent material, and a metallic bottle cap comprising a flat circular upper part and a flange forming a skirt extending around and out of the plane of said upper part, said cap being housed in said case with an outer surface of the upper part and skirt visible through the transparent upper face and middle of the case, a watch movement being housed in a space between an inner surface of the upper part of the bottle cap and an inner surface of the skirt of the bottle cap, a central hole being provided through the upper part of said bottle cap for the passageway of at least one pipe carrying a time indicating member rotatably driven above the upper part of said cap by means of said movement.
- 25 2. A watch according to claim 1, in which said inner surfaces of the upper part and skirt of the bottle cap are covered with a layer of synthetic material forming a support for the movement.
